UNITED STATES PATENT OFFICE.

ALBERT F. SCHROEDER AND RALPH R. ROOT, OF CLEVELAND, OHIO, ASSIGNEES TO THE
GLOBE MACHINE & STAMPING COMPANY, OF CLEVELAND, OHIO.

MANIFOLD.

1,271,779.

Specification of Letters Patent.

Patented July 9, 1918.

Application filed April 12, 1917. Serial No. 161,438.

To all whom it may concern:

Be it known that we, ALBERT F. SCHROEDER and RALPH R. Root, both citizens of the United States of America, residing at 5 1250 W. 76th st., city of Cleveland, in the county of Cuyahoga and State of Ohio, have invented a new and useful Improvement in Manifolds, of which the followings is a specification, the principle of the invention being 10 herein explained and the best mode in which we have contemplated applying that principle, so as to distinguish it from other inventions.

Our invention relates to a manifold such 15 as is in common use today in automobiles and more particularly to a manifold formed of more than one part and having the edges of the parts secured by what is known as a lock seam joint, wherein one edge is bent or 20 folded about another and thereafter the two laminated or tightly compressed.

We are well aware that such lock seam joints have long been in common use, indeed, the same has been employed for sealing the ends of tubes. We believe however, 25 that the application of such idea to the manufacture of a manifold having angularly presented branches is patentably new; bearing in mind the peculiarity of having all 30 the defining edges so secured together.

Adverting to the drawings:

Figure I is a perspective view of a manifold embodying our invention.

Fig. II is an end view of the same.

Fig. III is a section thereof showing the 35 complementary parts presented ready for the first operation.

Fig. IV is a view corresponding to Fig. II following the completion of the first operation.

Fig. V is a similar view after the completion of the second operation and also showing on one side a slightly modified result of such second operation.

Fig. VI is also a section illustrating the 45 final form of the lock seam joint.

Fig. VII is a perspective view of one portion of the manifold showing a completed corner formation.

The manifold comprises a trunk 1 having 50 branches each designated by the numeral 2.

According to the exemplification of the drawings the manifold is formed of only two parts which are substantially halves 3 and 4 respectively. As shown the halves 55 are of approximately semi-circular cross section. The part 3 has along one side a continuous flat flange 5 and along the other a series of four separated flat flanges 6 which are of various contour to form the 60 four branches of the manifold and are all designated by the numeral 6. The other part 4 has edges formed as hooked flanges. Along one side a continuous flange 7 is 65 formed, while on the other side a series of four separated hooked flanges are similarly 70 all designated as 8. The contour of the flange 7 and of the flanges 8 corresponds to that of the flange 5 and the flanges 6 respectively. The flanges 7 and 8 are of greater 75 width than the flanges 5 and 6 to the outline overall of which they are adapted to conform. This enables them to be bent and folded around the latter respectively, the progressive steps in the operation being 80 clearly indicated in Figs. II to VI. Finally spot welding is resorted to after the completion of the final operation of the series disclosed in the drawings, this welding operation along the lock seam being adequate 85 to insure the tightness of fit and strength which is required.

We claim:—

A manifold adapted for use in internal combustion aircraft engines comprising a 85 hollow structure shaped to form a main passageway and a plurality of branches extending therefrom to form corners, said manifold being manufactured of complementary light 90 sheet metal portions having continuous integral flat flanges around each of said corners as well as therebetween to constitute abutting edge portions, the latter being laminated, folded and welded together whereby to form 95 lock seams capable of maintaining a near vacuum within the manifold and sustaining both the high temperatures and the high pressures.

Signed by us, this 30th day of March, 1917.

ALBERT F. SCHROEDER.
RALPH R. ROOT.
